UNITED STATES PATENT OFFICE.

HJALMAR LINDESTROM, OF CHICAGO, ILLINOIS.

PRESSING-IRON.

1,116,900.

Specification of Letters Patent. Patented Nov. 10, 1914.

Application filed January 23, 1914. Serial No. 813,835.

To all whom it may concern:

Be it known that I, HJALMAR LINDESTROM, a citizen of the United States, residing at the city of Chicago, in the county 5 of Cook and State of Illinois, have invented certain new and useful Improvements in Pressing-Irons, of which the following is a specification.

This invention relates to improvements 10 in that type of irons which are heated by a mixture of gas and air supplied internally thereto, when used by tailors and large tailoring establishments for the purpose of pressing garments, the seams thereof, and cloth, and it consists in certain peculiarities of the construction, novel arrangement and operation of the various parts thereof, as will be hereinafter more fully set forth and specifically claimed.

20 The main object of my present invention is to provide an iron which shall be simple and inexpensive in construction, strong, durable and efficient in operation, and equipped with a distributing member 25 of such construction that the fuel or mixture of air and gas will be supplied to and discharged within the cavity of the iron in such a manner as to cause complete combustion thereof and uniform distribution 30 of heat, to the end that the ironing surface of the iron will be evenly and quickly heated.

Still another object is to provide simple and efficient means for preventing the handle and handle-plate from becoming overheated.

Other objects and advantages of the invention will be disclosed in the subjoined description and explanation.

40 In the accompanying drawings, which serve to illustrate the invention, Figure 1 is a view in side elevation of an iron embodying the invention; Fig. 2 is a longitudinal central sectional view thereof; Fig. 45 3 is a plan sectional view taken on line 3-3 of Fig. 2, looking in the direction indicated by the arrows; Fig. 4 is a cross sectional view taken on line 4-4 of Fig. 2; Fig. 5 is a rear end view of the iron, showing a portion of the distributing burner in section; Fig. 6 is a rear end view of the distributing burner detached from the iron. Fig. 7 is a plan view taken on line 50 7-7 of Fig. 8 of the lower portion of a modified form of the distributing burner,

and Fig. 8 is a cross sectional view taken on line 8-8 of Fig. 7.

Like numerals of reference refer to corresponding parts throughout the different views of the drawing.

The reference numeral 10 designates the body of the iron, which body is hollow and substantially rectangular in shape, but with its front end pointed, as is clearly shown in Fig. 3 of the drawings. Within 65 its cavity and at each of the rear corners thereof the body 10, is provided with a boss 11, which extends upwardly from the base 12 of the body a suitable distance to furnish rests for the distributing burner, which 70 is designated as a whole by the reference numeral 13, and which burner is substantially rectangular in shape, and has at its front end a downwardly and forwardly extended angle-foot 14 to rest on the base 12 75 of the body so as to support the front end of the burner. The front portion of the foot 14 is formed with a recess 15 to receive a lug 16, with which the body 10 is provided within its cavity at the lower portion of the front end thereof. Each side of the body 10 is provided just above the base 12, with a series of openings 17 for the admission of air to the interior of the body, and at its upper portion and on one side 80 thereof the body is provided with openings 18, which are also for the passage of air. These latter openings are by preference located on that side of the body opposite the operator in order that the heated 85 air passing therethrough may be directed from him.

As is clearly shown in Fig. 3, the burner 13 is provided with parallel channels 19, 20 and 21, and the channels 20 and 21 extend almost entirely the length of the body, while the channel 19 communicates with a cross channel 22, which communicates at its ends with the channels 20 and 21, which latter are provided in their lower surfaces 95 with perforations 23, for the escape of the mixture of air and gas. The tube or channel 19, has at its rear end an extension 24, which is externally screw threaded to engage a mixing member 25, which is cylindrical in shape, and has in its outer end a series of openings 26, for the passage of air into the cavity of the mixing member.

Mounted around the member 25 is a sleeve 27, which will direct air into the openings 110

26, as is obvious. Screwed into a suitable opening in the outer portion of the mixing member 25, is a pipe 28, which may be provided with a valve 29, for regulating the 5 flow of gas through said pipe. This pipe may be connected to a supply of gas by means of the flexible tube 30 and in the ordinary or any well-known manner.

As shown in the different views of the 10 drawings, the cavity of the body 10 is closed by means of a plate, which consists of two metal plates 31 and 32, with a layer of asbestos 33 or other non-heat conducting material interposed between said plates. Resting 15 on the non-heat conducting plate is a handle plate 34, which is provided at each of its corners with a depending lug 35, to rest on the plate 31, and said plates are secured to the body 10, by means of screws 20 36, located in the corners of the plates and seated in suitable openings in the body 10, near its corners.

Extended through the central portion of the handle-plate 34, is a screw bolt 37, which 25 also passes through a suitable opening in the cover plate of the body, and rests at its lower end on a cross piece 38, of the burner, by which means the latter is held firmly in place within the body of the iron. To prevent 30 any lateral movement of the burner 13, within the iron body, said burner is provided at its rear portion and on each side thereof with an extension 39, which rest against the inner surfaces or corners of the 35 iron body, as will be readily understood by reference to Fig. 3 of the drawings.

Located in the inner end of the pipe 28, is a jet-nozzle 40, which extends into the outer portion of the tubular part 24 of the channel 40 19, for the discharge of gas into and through said channel, in which operation it will be understood that a suction within the cavity of the member 25 will be created, so as to draw air through the openings 26, to be 45 mixed with the gas as it passes the passage-ways of the burner. The handle plate 34 is provided with a pair of uprights 41, which are connected at their upper ends by means of a handle 42, of wood or other suitable 50 material, and by which means the iron may be manipulated.

In Figs. 7 and 8 is shown the modification in the construction of the distributing burner, which modified form is more particularly intended to be used in connection 55 with small sad-irons for household purposes, but it will be understood that the same principle of distributing the fuel or mixture is involved in both of the constructions, and 60 furthermore, I desire it to be understood that the distributing burner 13 can be made of two counterpart pieces in a similar manner to those shown in the modified construction. In this modification the burner is 65 formed of two pieces 13^a, which are counter-

parts of one another, each having a central conduit 19^a into which the gas and air mixture is discharged in a manner similar to that shown in Fig. 3 and above described. On each side of the conduit or channel 19^a, 70 each of the pieces 13^a is formed with longitudinally extending channels 20^a and 21^a, which communicate with one another at their front ends, and also with the channel 19^a. The floors of the longitudinally extending channels are provided with perforations 23^a in order that the mixture may pass downwardly into the iron body and against the lower surface thereof. By making the burner of two parts and securing them together by means of screws, as shown in Fig. 8, it is apparent that they can be more readily cast and made at less expense than if the burner should be made of a single piece, and for this reason, in some instances, I may 80 construct the burner 13 of two counterpart pieces.

From the foregoing and by reference to the drawings, it will be readily understood and clearly seen, that by supplying gas 90 through the tube 30, pipe 28, and jet-nozzle 40, to the burner, a mixture of air and gas will be produced by reason of the air entering through the openings 26 of the mixing chamber, and that the said mixture will pass 95 downwardly through the openings 23 in the burner 13, and openings 23^a when the burner 13^a is used, where it can be ignited by the means of a match inserted in the rear end of the body beneath the burner. As the 100 mixture is directed downwardly against the base or ironing surface 12 and throughout almost its entire length, it is obvious that said portion of the iron will be quickly and uniformly heated, and that as air will be 105 supplied to the cavity of the iron body through the openings 17 and rear portion of said body, it is manifest that complete combustion of the mixture will take place.

Having thus fully described my invention, what I claim as new and desire to secure by Letters Patent, is—

1. An iron consisting of a hollow body having an opening in one of its ends and provided near said end with bosses extended 115 upwardly from the bottom, a lug at the lower inner portion of the other end of the body, a distributing-burner horizontally located within the body and having at one of its ends a foot to engage said lug and at its other end extensions to rest on the said bosses, said burner having a pair of parallel and perforated conduits extended longitudinally therein and also having at one of its ends a conduit intermediate the parallel conduits but communicating therewith at its inner end, means to force the burner against said bosses, and a fuel supply pipe connected to the outer end of the intermediate conduit. 120

2. An iron consisting of a hollow body 130

- having an opening in one of its ends and provided near said end with bosses extended upwardly from the bottom, a lug at the lower inner portion of the other end of the body, a distributing-burner horizontally located within the body and having at one of its ends a foot to engage said lug and at its other end extensions to rest on the said bosses, said burner having a pair of parallel 5 conduits and perforated conduits extended longitudinally therein and also having at one of its ends a conduit intermediate the parallel conduits but communicating therewith at its inner end, a screw bolt extended through the 10 top of the body and resting against the burner to hold the same in contact with said bosses and the bottom of the body, and a fuel supply pipe connected to the outer end of the intermediate conduit.
- 20 3. An iron consisting of a hollow body having an opening in one of its ends, a skeleton distributing-burner horizontally located within the body at a distance from its bottom and having a pair of parallel and per- 25 forated conduits extended longitudinally therein, said burner also having at one of its ends a conduit intermediate the parallel con-

duits but communicating therewith at its inner end, means to hold the burner within the body against movement, a mixing member 30 mounted on the outer portion of the intermediate conduit and having openings in its outer portion, a sleeve surrounding the outer portion of the mixing member, and a fuel supply pipe connected to said mixing 35 member within the sleeve.

4. An iron consisting of a hollow body having an opening in one of its ends, a distributing burner horizontally located within the body at a distance from its bottom and 40 consisting of two counterpart pieces connected together and having a pair of longitudinally extended and perforated conduits, said burner also having at one of its end a conduit intermediate the longitudinal conduits but communicating therewith at its inner end, and a fuel supply pipe connected to the outer end of said intermediate conduit. 45
